US00D737254S

(12) **United States Design Patent**
Mun et al.

(10) **Patent No.:** US D737,254 S
(45) **Date of Patent:** ** Aug. 25, 2015

(54) **MICROPHONE MOUNT ASSEMBLY**

(71) Applicant: **Freedman Electronics Pty Limited**,
Silverwater NSW (AU)

(72) Inventors: **Sung Hoon Mun**, Silverwater (AU);
Mohammadreza Ghanavi, Silverwater (AU)

(73) Assignee: **Freedman Electronics Pty Limited**,
Silverwater, New South Wales (AU)

(**) Term: **14 Years**

(21) Appl. No.: **29/473,550**

(22) Filed: **Nov. 22, 2013**

(51) **LOC (10) Cl.** 14-01

(52) **U.S. Cl.**

USPC **D14/229**

(58) **Field of Classification Search**

(57) **CLAIM**

The ornamental design for a microphone mount assembly, as shown and described.

DESCRIPTION

FIG. 1 is a bottom view of a microphone mount assembly, showing our new design;

FIG. 2 is a front view of the design;

FIG. 3 is a isometric view of the design;

FIG. 4 is a isometric view of the design;

FIG. 5 is a rear view of the design;

FIG. 6 is a side view of the design; and,

FIG. 7 is a top view of the design.

The broken lines in FIG. 1 depict parts of the microphone mount assembly that form no part of the claimed design.

1 Claim, 7 Drawing Sheets
